POWER SHOVEL

Charles E. Stoltz, Chicago, Ill., assignor to
 Mancha Storage Battery Locomotive Company,
 Chicago, Ill., a corporation of Illinois

Application April 20, 1935, Serial No. 17,419

19 Claims. (Cl. 214—132)

This invention relates to improvements in power shovels of the mucking type adapted to shovel muck or other materials in mines underground and discharge it into a car or like receptacle disposed rearwardly thereof.

Among the objects of my invention are to provide a new and improved mucker of a size which will readily fit in a mine cage, arranged with a view towards compactness and efficiency in operation. Another object of my invention is to provide a new and improved operating mechanism for the scoop or shovel including a novel controlling means for moving the shovel longitudinally of the machine into the material to be loaded during the initial shoveling operation, together with a new and improved means for controlling movement of the shovel to a discharge point rearwardly of its supporting truck and returning it to its initial gathering or loading position.

My invention may be more clearly understood with reference to the accompanying drawings, wherein:

Figure 1 is a side elevation of a shoveling machine illustrating one form in which my invention may be embodied, with certain parts broken away and shown in longitudinal section;

Figure 2 is a top plan view of the embodiment of my invention shown in Figure 1;

Figure 3 is a transverse sectional view taken substantially along line 3—3 of Figure 1;

Figure 4 is a sectional view taken substantially along line 4—4 of Figure 1;

Figure 5 is a fragmentary top plan view of the device shown in Figure 1, with the shovel frame, positioned differently than in Figure 1, and with the shovel and supporting beams therefor broken away and shown in section to clearly show one form of mechanism for aligning the scoop while discharging material therefrom;

Figure 6 is a fragmentary plan view similar to Figure 5, with certain other parts broken away and in section, and the shovel frame in a different position than in Figure 5;

Figure 7 is an enlarged sectional view taken substantially along line 7—7 of Figure 5;

Figure 8 is a fragmentary plan view similar to Figure 5, but showing a modified form of mechanism for aligning the shovel frame and scoop while discharging material therefrom;

Figure 9 is a fragmentary plan view similar to Figure 8, showing the shovel frame in a different position than in Figure 8;

Figure 10 is a sectional view taken substantially along line 10—10 of Figure 8;

Figure 11 is a sectional view taken substantially along line 11—11 of Figure 9;

Figures 12, 13, 14 and 15 are diagrammatical views of the embodiment of my invention illustrated in Figure 1, showing various stages of the operating cycle thereof; and

Figure 16 is a diagrammatical view showing the shovel arranged to be loaded onto a mine cage.

In the drawings the embodiment of my invention illustrated includes a truck 10 which comprises a frame 11 mounted on track wheels 12, 12 and axles 13, 13 in a suitable manner. A turntable or shovel frame 14 is supported on said truck frame for movement with respect thereto about a vertical axis disposed adjacent the center of said truck frame.

The turntable includes a bottom plate 15 pivotally mounted on a boss 16 formed integral with and extending upwardly from the truck frame. Balls 17, 17 carried in an annular guideway 18 having an outer diameter equal substantially to the outer boundaries of the truck frame form an anti-friction support for said turntable (see Figure 3).

A scoop 20 is pivotally supported adjacent its upper or discharge end on a transverse shaft 23 which is mounted adjacent its ends on the free ends of a pair of parallel-spaced beams 21, 21. Said shaft is connected to a bracket 24 secured to and extending rearwardly from said scoop and abutting the inner sides of said beams and is held from lateral movement with respect to said beams by means of pins 25, 25. The opposite ends of said beams are secured to a transverse shaft 27 which, as herein shown, is journaled at its ends in the hubs of a pair of parallel-spaced vertically arranged aligned gear sectors 29, 29 extending upwardly from the frame 14. Said gear sectors are secured to opposite sides of the frame 14 and are so arranged that a line extending through the center of their hubs intersects the boss 16.

The scoop 20 is adapted to depend downwardly from the beams 21, 21 during the initial gathering operation, as is best shown in Figure 1. Said scoop is provided with a digging edge 30 having spaced-apart digging teeth 31, 31 projecting forwardly therefrom so that said digging edge and teeth may engage and slide along the ground for picking up loose material therefrom.

The beams 21, 21 are simultaneously swung about the axis of the shaft 27 for elevating said scoop and positioning it for discharging material into a suitable car 32 or like receptacle dis-

posed rearwardly of the truck by means of gears 33, 33 keyed to opposite ends of a transverse shaft 34. Said shaft is journaled in said beams intermediate the ends thereof and said gears mesh with the teeth of the gear sectors 29, 29.

A motor 35 is secured to the turntable or shovel frame 14 adjacent the rearward end thereof between the gear sectors 29, 29 for driving the gears 33, 33. Said motor may be of any type, but is herein preferably shown as being an air motor of a standard construction, well known to those skilled in the art. Said motor is provided with a transversely extending motor shaft 36 having a sprocket 37 keyed thereon. A sprocket 39 is freely mounted on the transverse shaft 27 between one beam 21 and one gear sector 29 and is driven from the sprocket 37 by means of a drive chain 40. Another sprocket 41 is freely mounted on the transverse shaft 27 adjacent the sprocket 39 and is herein shown as being formed integral therewith and driven thereby. Said sprocket has driving connection with the transverse shaft 34 by means of a chain and sprocket drive, generally indicated by reference character 43. It will thus be apparent that when the motor 35 is driven in one direction, the spur gears 33, 33 will rotate along the gear sectors 29, 29 and simultaneously pivot the beams 21, 21 about the axis of the transverse shaft 27.

Suitable means (not shown) may be provided to stop the motor 35 and movement of the beams 21, 21 when they reach the extreme ends of their path of travel in either direction. If desired, said means may also act as a means for reversing the direction of rotation of the motor 35. Said means forms no part of my present invention so is not herein shown or described in detail.

Referring now in particular to the novel means for controlling movement of the scoop during the gathering and loading operations and moving said scoop longitudinally forwardly into the material during the initial gathering operation, said means, as herein shown, includes a controlling link 44. Said link is pivoted adjacent one of its ends to a transverse shaft 45 carried in suitable brackets 46, 46 extending rearwardly from said scoop adjacent opposite sides thereof. Said brackets are spaced downwardly from the bracket 50 24 a substantial distance, when said scoop is positioned as in Figure 1. Said controlling link is slotted for a portion of its length and the slotted portion thereof slidably engages a roller 47 on the transverse shaft 34. The end of said link opposite the scoop 20 is provided with a notch 49 communicating with the slotted portion of said link and offset rearwardly and downwardly therefrom when in the position shown in Figure 1.

A guiding member 50 is provided adjacent the forward end of the shovel frame 14 for engaging the lower rearward surface of the controlling link 44. Said guiding member may be of any construction, but is herein shown as being a flanged anti-friction roller mounted on a horizontal shaft 51. Said shaft is mounted in an adjustable bracket 52 which, as herein shown, is of a bifurcated formation having its prongs extending towards the forward end of the machine and having said shaft mounted between said prongs. The under surfaces of the prongs of said bracket are beveled downwardly towards the rearward end of the frame and the beveled surfaces thereof engage beveled wedges 58, 58 secured to the forward end of the turntable 14 and extending up-

wardly and forwardly therefrom. A lug 61 extends angularly upwardly from the central portion of the bracket 52 and has a threaded shaft 62 secured thereto and extending angularly downwardly and rearwardly therefrom in a plane parallel to the angle of the wedges 58. The opposite end of said shaft is slidably mounted in a lug 63 on the turntable 14. A hand wheel 64 is threaded on said shaft between the lugs 61 and 63 and abuts the lug 63. Thus, rotation of said hand wheel in one direction will elevate and move the roller 50 forwardly along the turntable 14 and elevate the forward end of said scoop to compensate for increased distances between the top of the rail to the ground; and rotation of said hand wheel in an opposite direction will lower the forward end of said scoop.

It should be observed that when the beams 21, 21 are moving in a forward direction from a position similar to that illustrated in Figure 1, to a position such as is illustrated in Figure 12, and the guiding member 50 engages the rearward face of the controlling link 44, that the reaction of said guiding member against said controlling link pivots the shovel or scoop 20 in a forward direction about its axis of pivotal connection to the beams 21, 21 and thus moves the forward end of said scoop longitudinally forwardly of the truck along the ground. As said link reaches the end of its longitudinal travel with respect to said beams, said guiding member engages the roller 47 with the notch 49 and locks said controlling link from slidable movement with respect to said beams, as is diagrammatically illustrated in Figure 12. At this point the limit of downward travel of the beams 21, 21 is reached and reverse movement of the gears 33, 33 will elevate said beams and swing the forward end of the scoop 20 in an upward direction until a position is reached, such as is indicated in Figure 13.

Means are provided for guiding and controlling movement of the scoop 20 from a position such as is shown in Figure 13, to the discharge position illustrated by dotted lines in Figure 1, which means, as herein shown, comprises a pair of 45 guide cams 53, 53. Said guide cams are secured to the inner sides of opposite side plates 54, 54 which extend upwardly from and are secured to opposite sides of the frame 14 adjacent the outer sides of the gear sectors 29, 29. Each of said guide cams is provided with a depending relatively blunt rounded forward end spaced forwardly of and above the forward end of the frame 14. From said forward end, said cams are inclined upwardly at a gradual inclination to a point disposed rearwardly of the center of said frame, from which point the angle of inclination of said cams increases to guide the forward or engaging end of the scoop in an upward direction.

Suitable rollers 55, 55 are mounted on the outer ends of the transverse shaft 45 and are adapted to engage and support said scoop for movement along said guide cams. Thus, upon upward movement of the beams 21, 21 said guide cams 65 will be engaged by said rollers and will elevate and move the forward end of the scoop 20 forwardly a distance sufficient to disengage the transverse shaft 34 from the notch 49, and support the forward portion of said scoop in a relatively retracted loaded position, during movement toward the rearward or discharge end of the frame 14, as is illustrated in Figure 14.

Stops 56, 56 are provided on the inner sides of the side plates 54, 54 in alignment with, but 75

spaced upwardly from upturned rearward ends of the guide cams 53, 53 for engaging the rollers 55, 55. Said stops thus limit upward pivotal movement of said scoop and hold it in the discharge position, illustrated by dotted lines in Figure 1.

Each stop 56, as herein shown, has a concave engaging surface conforming to the circumference of the roller 55 and is yieldably mounted in a bracket 57 secured to the side plate 54 so as to be slidably movable with respect thereto against compression springs 58a, 58a (see Figure 4).

Guide cams 59, 59 are provided rearwardly of and extend downwardly beneath the guide cams 53, 53 toward the forward end of the side plates 54, 54. Said guide cams each have an upturned upper end 60 in alignment with the stops 56 and are adapted to engage the rollers 55 and support and guide the scoop 20 to an initial gathering position, upon movement of the beams 21, 21 in a clockwise direction, in the manner illustrated in Figure 15.

It will thus be apparent that upon movement of the beams 21, 21 in a clockwise direction from a position shown in Figures 12 and 15, that the scoop will first be lowered to a position adjacent the ground, and as it approaches the ground it will be moved longitudinally of the truck into the material to be gathered by the controlling link 44 which engages the guiding member 50, as is best illustrated in Figures 1 and 12.

Upon reverse or counter-clockwise movement of said beams, the forward end of the scoop 20 is pivoted in an upward direction about its axis of pivotal connection to the beams 21, 21 until the rollers 55, 55 engage the forward ends of the guide cams 53, 53 when the notch 49 is disengaged from the transverse shaft 34. The rearward portion of said scoop is supported on said guide cams while being moved rearwardly along the frame 14 until it reaches the rearward end of said guide cams when its forward end is pivoted upwardly about its axis of pivotal connection to the beams 21, 21 and the rollers 55, 55 are engaged with the spring-pressed stops 56, 56 from which position material is discharged therefrom into the car 32. Upon reverse movement of said beams, the rollers 55, 55 engage the guide cams 59, 59 and support the forward end of said scoop for downward movement along said guide cams, as is shown in Figure 14, until it reaches the initial loading position, shown in Figures 1 and 11.

The turntable or shovel frame 14 may be turned in any suitable manner for positioning the scoop for gathering material from opposite sides of the track, but for the purpose of simplicity, said turntable is herein preferably shown as being manually turned.

A centering mechanism of a novel construction is provided for aligning said turntable with the truck frame when the scoop is in a discharge position, so that material may be discharged from the same point from the rear of the truck regardless of the position of the turntable with respect to the truck during the gathering operation. Said means, as shown in detail in Figures 2, 3, 6 and 7, includes a depending lever arm 65 keyed to the transverse shaft 27. The lower portion of said lever arm tapers to a longitudinally extending wedge-shaped point. Said lower tapered sides of said lever arm are adapted to engage the sides of a stationary cam 66 shaped

substantially in the form of a Y and open towards the rearward end of the frame.

Said cam, as herein shown, is formed from an upstanding portion of the boss 16 and is so arranged that when the scoop 20 is in a lowered position the turntable 14 is free to turn a predetermined amount to permit the scoop to be positioned to either side of the track. When said turntable is positioned, as shown by either dotted or solid lines in Figure 5, one of the wedge-shaped sides of the lever arm 65 will engage a slot formed from the stem of the Y and upon pivotal movement of the shaft 27 in a counter-clockwise direction will swing said turntable to a position in alignment with the frame 11, as is illustrated in Figures 5 and 6. It should be noted that when the scoop is in a discharge position, said engaging member is engaged with the stem of the Y-shaped cam 66 and the frames 11 and 14 are locked in fixed relation with respect to each other, but that when the beams 21, 21 are in a forward lower position, said engaging member is disengaged from said slot to permit pivotal movement of the frame 14 with respect to the frame 11 to either side of the center line thereof.

Referring now particularly to the modified form of device for aligning the frames 11 and 14, illustrated in Figures 8 to 11, inclusive, the boss 16 is shown as being of less vertical dimensions than in Figure 1, and has a plate 69 secured to its top surface. A fixed cam member 70 extends upwardly from said plate and has opposite spaced-apart vertical beveled surfaces 71, 71 extending angularly inwardly toward the rearward end of the frame 11. Parallel-spaced engaging members 72, 72 are keyed to the transverse shaft 27 inwardly of the beams 21, 21 for engagement with the beveled surfaces of said cam members. Said engaging members depend from the shaft 27 and are herein shown as being formed in the shape of a segment of a circle. Each of said engaging members has a forward radial side 72a, and an inner beveled arcuate edge 73. When the frame 14 is positioned in an extreme position to one side of the frame 11 as in Figure 8, the radial side 72a of said engaging member will engage the beveled face 71 of the cam member 70 (see Figure 10). As said engaging member pivots about the axis of the shaft 27, it will simultaneously pivot the frame 14 and align said frame with respect to the truck. When in such a position the beveled surface 73 will engage the beveled surface of said cam member and both of said engaging members will act as a stop to prevent movement of the turntable 14 beyond an aligned position in either direction.

It will thus be apparent that the device of my invention is so arranged that the scoop is automatically positioned so as to extend longitudinally of the frame when it is positioned for discharging material into a mine car. It may also be seen that said aligning means is of a simplified construction which effects movement of the swinging frame 14 in a simple and efficient manner with a minimum amount of moving parts.

A suitable means is provided for propelling the machine along the rails and moving the scoop into engagement with the material it is desired to load. Said means, as herein shown, comprises a motor 74 which may be of any type, but which is herein preferably shown as being an air motor similar to the motor 35. Said motor is provided with a motor sprocket 75 which has drive connection with the forward truck axle by means of a chain and sprocket drive, generally indicated 75

by reference character 76. The forward and rearward truck axles 13, 13 are operatively connected together by means of a chain and sprocket drive, generally indicated by reference character 5 77.

10 Suitable means are provided for holding the scoop in a retracted position with respect to the truck 10 when it is desired to move from working place to working place, and when it is desired to 15 place the machine in the mine cage for moving it from one level to another in the mine. Said means, as herein shown, comprises a plurality of aligned apertures 79, 79 formed in the side plates 54, 54 between the guide cams 53 and 53 which 20 may be engaged by suitable pins, indicated by reference character 80 in Figure 4. Said scoop is moved upwardly along the guide cams 53, 53 until its forward end is in alignment with the forward end of the side plates 54, 54. The pins 80, 80 25 may then be inserted in the apertures 79, 79 forwardly of the brackets 46, 46. Thus, when the scoop is in such a position, the entire mechanism is within the forward boundaries of the side plates 54, 54, and the rearward boundaries of the truck 10 and utilizes a minimum amount of longitudinal 30 space, which permits the entire device to be moved in the average mine cage.

35 While I have herein shown and described one form in which my invention may be embodied, it will be understood that the construction and arrangement of the various parts may be changed or altered without departing from the spirit or scope thereof. Furthermore, I do not wish to be construed as limiting myself to the precise construction illustrated, excepting as it may be limited in the appended claims.

I claim as my invention:

1. In a power shovel, the combination of a 40 frame, a beam horizontally pivoted on said frame, a scoop pivoted on said beam, means for swinging said beam about a horizontal axis, and means for controlling movement of said scoop upon swinging movement of said beam and moving the forward end of said scoop longitudinally forwardly of said frame and thence upwardly to a discharge point rearwardly of said frame including a controlling member extending rearwardly from said scoop at a point spaced downwardly from the axis of pivotal connection of said beam thereto when said scoop is in a loading position, and a 45 adapted to be actuated by engagement with said frame for moving said scoop forwardly of said frame during the last part of the downward and initial upward movement of said beam, and a supporting guide on said frame extending longitudinally therealong adapted to have supporting engagement with said scoop for guiding and supporting said scoop in a loaded condition to a discharge position beyond the rearward end of said frame.

50 2. In a power shovel, the combination of a frame, a beam horizontally pivoted on said frame, a scoop pivoted on said beam, means for swinging said beam about a horizontal axis, and means for controlling movement of said scoop upon swinging movement of said beam and moving the forward end of said scoop longitudinally forwardly of said frame and thence upwardly to a discharge point rearwardly of said frame including a controlling member extending rearwardly from said scoop at a point spaced downwardly from the axis of pivotal connection of said beam thereto when said scoop is in a loading position, and a 55 adapted to be actuated by engagement with said frame upon movement of said beam, for moving

5 said scoop forwardly of said frame during the last part of the downward and initial upward movement of said scoop, a supporting guide on said frame extending longitudinally therealong adapted to have supporting engagement with said scoop for guiding and supporting said scoop in a loaded condition to a point disposed adjacent the rearward end of said frame, and pivot said scoop about its axis of pivotal connection to said beam to an extended relatively upright discharge position adjacent the rearward end thereof, and another guide beneath said first guide for guiding said scoop to an initial loading position.

10 3. In a power shovel, the combination of a frame, a beam pivoted to said frame adjacent one of its ends for movement with respect thereto about a horizontal axis, a scoop pivotally supported by said beam in such a manner as to overhang said frame when said beam is in a lowered position so that a forwardly disposed digging lip 15 may be adjacent the ground, means for swinging said beam about its axis of pivotal connection to said frame, and means for controlling movement of said scoop upon swinging movement of said beam for moving the forward end of said scoop longitudinally forwardly along the ground as said beam approaches the forward end of said frame and continuing said forward movement of said scoop, and simultaneously pivoting said scoop 20 in an upward direction and elevating said scoop upon pivotal movement of said beam in a rearward direction comprising a controlling member extending from said scoop at a point spaced downwardly from said beam when said scoop is 25 in a loading position, and a member on said frame adapted to engage said controlling member and cause said scoop to be moved in a forward and upward direction, upon engagement with said controlling member.

30 4. In a power shovel, the combination of a frame, a beam pivoted to said frame adjacent one of its ends for movement with respect thereto about a horizontal axis, a scoop pivotally supported by said beam in such a manner as to overhang said frame when said beam is in a lowered position so that a forwardly disposed digging lip 35 may be adjacent the ground, means for swinging said beam about its axis of pivotal connection to said frame, and means for controlling movement of said scoop upon swinging movement of said beam for moving the forward end of said scoop longitudinally forwardly along the ground as said beam approaches the forward end of said frame and continuing said forward movement of said scoop, and simultaneously pivoting said scoop in an upward direction and elevating said scoop upon pivotal movement of said beam in a rearward direction comprising a controlling member 40 extending from said scoop at a point spaced downwardly from said beam when said scoop is in a loading position, and a member on the forward end of said frame adapted to engage said controlling member and cause said scoop to be moved in a forward and upward direction upon engagement with said controlling member, and a guide on said frame extending longitudinally therealong adapted to be engaged by said scoop for supporting said scoop in a retracted loaded position with respect to said frame, and extending said scoop to a relatively upright discharge position at 45 the discharge end of said frame.

55 5. In a power shovel, the combination of a frame, a beam horizontally pivoted on said frame, a scoop pivoted on said beam, means for swing-

ing said beam, and means for controlling movement of said scoop upon swinging movement of said beam and moving the forward end of said scoop longitudinally forwardly of said frame and 5 thence upwardly to a discharge point rearwardly of said frame including a controlling link pivoted to said scoop at a point spaced from the axis of pivotal connection of said beam thereto, said link having slidable engagement with said beam, and 10 means on said frame adapted to engage said controlling link and control movement of said scoop upon downward swinging movement of said beam and lock said controlling link from translational movement with respect to said beam during the 15 initial upward swinging movement thereof.

6. A power shovel in accordance with claim 5, wherein the controlling link is slotted for a portion of its length and is provided with a notch at its end opposite said scoop which communicates 20 with said slot, wherein a guiding member is provided on said beam for slidably engaging said slot, and wherein downward movement of said beam to an extreme lowermost position acts to engage said member with said notch for locking said 25 link from slidable movement with respect to said beam during initial upward movement thereof.

7. A power shovel in accordance with claim 5, wherein the controlling link is slotted for a portion of its length and is provided with a notch 30 at its end opposite said scoop which communicates with said slot, wherein said slot is slidably engaged by a guiding member on said beam, and wherein a member is provided on the forward end of said frame which is adapted to be engaged by said controlling link for controlling movement thereof and engaging said guiding member with said notch when said beam is in an extreme lowermost position, for locking said 35 link from slidable movement with respect to said beam during initial upward movement thereof.

8. A power shovel in accordance with claim 5, wherein the controlling link is slotted for a portion of its length and is provided with a notch 40 at its end opposite said scoop which communicates with said slot, wherein a guiding member is provided on said beam for slidably engaging said slot, wherein downward movement of said beam to an extreme lowermost position acts to engage said member with said notch for locking said 45 link from slidable movement with respect to said beam during initial upward movement thereof, and wherein a guide is provided on said frame which is adapted to be engaged by said scoop for releasing said notch from said guiding member 50 and guiding said scoop in a loaded position during rearward movement thereof along said frame to a discharge position.

9. A power shovel in accordance with claim 5, wherein the controlling link is slotted for a portion 55 of its length and is provided with a notch at its end opposite said scoop communicating with said slot, wherein a guiding member is provided on said beam for slidably engaging said slot, wherein downward movement of said beam to an extreme lowermost position acts to engage said member with said notch for locking said link from slidable movement with respect to said beam during initial upward movement of said scoop, wherein a guide is provided on said frame which 60 is adapted to be engaged by said scoop for releasing said notch from said guiding member and guiding said scoop in a loaded position during rearward movement thereof along said frame to a discharge position, and wherein said guide is 65 adapted to pivot said scoop about its axis of piv- 70

otal connection to said beam to an extended relatively upright discharge position with respect to said frame adjacent the rearward end thereof.

10. A power shovel in accordance with claim 5, 5 wherein the controlling link is slotted for a portion of its length and is provided with a notch at its end opposite said scoop communicating with said slot, wherein a guiding member is provided on said beam for slidably engaging said slot, wherein downward movement of said beam to an extreme lowermost position acts to engage said member with said notch for locking said link from slidable movement with respect to said beam during initial upward movement thereof, wherein 10 a guide is provided on said frame which is adapted to be engaged by said scoop for releasing said notch from said guiding member and guiding said scoop in a loaded position during rearward movement thereof along said frame to a discharge position, wherein said guide is adapted 15 to pivot said scoop about its axis of pivotal connection to said beam to an extended relatively upright discharge position with respect to said frame adjacent the rearward end thereof, and wherein another guide is provided on said frame beneath said first guide for guiding said scoop to an initial loading position.

11. In a power shovel, the combination of a frame, a beam horizontally pivoted on said frame, a scoop pivoted on said beam, means for swinging said beam about a horizontal axis, and means for controlling movement of said scoop upon swinging movement of said beam and moving the forward end of said scoop longitudinally forwardly of said frame and thence upwardly to a discharge point rearwardly of said frame including a controlling link pivoted to said scoop at a point spaced from the axis of pivotal connection of said beam thereto, said link being slotted for a portion of its length and being provided with a notch at its end opposite said scoop communicating with said slot, a guiding member on said beam having slidable engagement with said slot whereby downward movement of said beam to an extreme lowermost position acts to engage said member with said notch for locking said link from slidable movement with respect to said beam during initial upward movement of said scoop, a guide on said frame adapted to be engaged by said scoop for releasing said 30 notch from said guiding member and guiding said scoop in a loaded position during rearward movement thereof along said frame to a discharge position, and adapted to pivot said scoop about its axis of pivotal connection to said beam to an extended relatively upright discharge position adjacent the rearward end thereof.

12. In a power shovel, the combination of a frame, a beam horizontally pivoted on said frame, a scoop pivoted on said beam, means for swinging said beam about a horizontal axis, and means for controlling movement of said scoop upon swinging movement of said beam and moving the forward end of said scoop longitudinally forwardly of said frame and thence upwardly to a discharge point rearwardly of said frame including a controlling link pivoted to said scoop at a point spaced from the axis of pivotal connection of said beam thereto, said link being slotted for a portion of its length and being provided with a notch at its end opposite said scoop communicating with said slot, a guiding member on said beam having slidable engagement with said slot whereby downward movement of said beam to an extreme lowermost position acts to engage said member with said notch for locking said link from slidable movement with respect to said beam during initial upward movement of said scoop, a guide on said frame adapted to be engaged by said scoop for releasing said notch from said guiding member and guiding said scoop in a loaded position during rearward movement thereof along said frame to a discharge position, and adapted to pivot said scoop about its axis of pivotal connection to said beam to an extended relatively upright discharge position adjacent the rearward end thereof.

ber with said notch for locking said link from 5
slidable movement with respect to said beam during initial upward movement of said scoop, a
guide on said frame adapted to be engaged by
5 said scoop for releasing said notch from said
guiding member and guiding said scoop in a
loaded position during rearward movement
thereof along said frame to a discharge position,
and adapted to pivot said scoop about its axis
10 of pivotal connection to said beam to an extended
relatively upright discharge position adjacent the
rearward end thereof, and another guide on said
frame beneath said first guide for guiding said
scoop to an initial loading position.

15 13. In a power shovel, the combination of a
frame, a beam pivoted to said frame adjacent
one of its ends for movement with respect thereto
about a horizontal axis, a scoop pivoted at its
upper end to the free end of said beam in such
20 a manner as to overhang said frame so that a
forwardly disposed digging lip on said scoop may
be disposed adjacent the ground when said beam
extends forwardly of said frame in lowered position
with respect thereto, means for swinging
25 said beam about its axis of pivotal connection to
said frame, and means for controlling movement
of said scoop upon swinging movement of said
beam for moving the forward end of said scoop
longitudinally forwardly along the ground as said
30 beam approaches the forward end of said frame
and continuing said forward movement of said
scoop, and simultaneously pivoting said scoop
in an upward direction about its axis of pivotal
connection to said beam and elevating said scoop
35 upon pivotal movement of said beam in a rear-
ward direction comprising a controlling link piv-
otally connected to said scoop at a point spaced
downwardly from the axis of pivotal connection
of said beam to said scoop when said scoop is in
40 a loading position and having slidably connec-
tion with said beam and adapted to be locked
from slidable movement with respect to said beam
when said scoop is in a lowermost position with
respect to said frame and during the initial up-
45 ward movement thereof, and means on said
frame for engaging said controlling link and con-
trolling movement thereof.

14. A power shovel in accordance with claim
13, wherein the controlling link is slotted for a
50 portion of its length and is provided with a notch
at its end opposite said scoop communicating
with said slot, wherein a guiding member is pro-
vided on said beam for slidably engaging said
slot and wherein said means on said frame en-
55 gaging said controlling link acts to move the
scoop forwardly into the material upon downward
movement of said beam and engage said slot
with said guiding member upon the completion
of downward movement of said beam for pivot-
60 ing the forward end of said scoop upwardly upon
upward movement of said beam.

15. A power shovel in accordance with claim
13, wherein the controlling link is slotted for a
portion of its length and is provided with a notch
65 at its end opposite said scoop communicating
with said slot, wherein a guiding member is pro-
vided on said beam for slidably engaging said
slot and wherein said means on said frame en-
gaging said controlling link acts to move the
70 scoop forwardly into the material upon downward
movement of said beam and engage said slot
with said guiding member upon the completion
of downward movement of said beam, for pivot-
ing the forward end of said scoop upwardly upon
75 upward movement of said beam, and wherein a

guide is provided which is adapted to be engaged
by means on said scoop disposed adjacent the
axis of pivotal connection of said link thereto for
disengaging said notch from said guiding mem-
ber and supporting said scoop in a retracted load-
5 ed position with respect to said beam during
movement towards a discharge position, and ex-
tending said scoop to a relatively upright dis-
charge position at the discharge end of said
frame.

10 16. A power shovel in accordance with claim 13
wherein the controlling link is slotted for a por-
tion of its length and is provided with a notch
at its end opposite said scoop communicating
with said slot, wherein a guiding member is pro-
vided on said beam for slidably engaging said
slot and wherein said means on said frame en-
gaging said controlling link acts to move the
scoop forwardly into the material upon downward
movement of said beam and engage said slot with
15 said guiding member upon the completion of
downward movement of said beam for pivoting
the forward end of said scoop upwardly upon up-
ward movement of said beam, wherein a guide
is provided which is adapted to be engaged by
20 means on said scoop disposed adjacent the axis
of pivotal connection of said link thereto for
disengaging said notch from said guiding mem-
ber and supporting said scoop in a retracted loaded
position with respect to said beam during move-
25 ment towards a discharge position and extending
said scoop to a relatively upright discharge posi-
tion at the discharge end of said frame, and
wherein another guide is spaced rearwardly from
said first-mentioned guide for engaging said
30 means on said scoop and guiding said scoop to
an initial loading position.

35 17. A power shovel in accordance with claim 13,
wherein the controlling link is slotted for a por-
tion of its length and is provided with a notch
at its end opposite said scoop communicating
with said slot, wherein a guiding member is pro-
40 vided on said beam for slidably engaging said slot
and wherein said means on said frame engaging
said controlling link acts to move the scoop for-
wardly into the material upon downward move-
45 ment of said beam and engage said slot with
said guiding member upon the completion of
downward movement of said beam for pivoting
the forward end of said scoop upwardly upon up-
ward movement of said beam, wherein a guide is
50 provided which is adapted to be engaged by means
on said scoop disposed adjacent the axis of pivotal
connection of said link thereto for disengaging
said notch from said guiding member and sup-
porting said scoop in a retracted loaded position
55 with respect to said beam during movement to-
wards a discharge position and pivoting said scoop
about its axis of pivotal connection to said beam
to a discharge position, wherein a stop is adapt-
ed to engage said scoop at the completion of its
60 upward path of travel, and wherein another guide
is spaced rearwardly of and extends beneath said
first-mentioned guide for guiding said scoop to an
initial loading position.

65 18. In a power shovel, the combination with
a frame, a beam horizontally pivoted on said
frame having a scoop pivoted to the free end
thereof, means on said frame for elevating said
beam and scoop for discharging material rear-
70 wardly of said frame comprising a gear segment
on said frame, a gear on said beam meshing with
said gear segment, and power means for driving
said gear, and means for controlling movement
of said scoop and moving said scoop longitudinally
75 forwardly along the ground during the initial

gathering operation comprising a slotted controlling link pivoted to said scoop at a point spaced downwardly from the axis of pivotal connection of said beam thereto, when said scoop is in an initial gathering position, and having slidable engagement with said beam in said slot, said slot leading to a notch at the end of said controlling link opposite the point of connection of said link to said scoop, and a member on said frame adapted to engage the rearward face of said link for initially swinging said scoop longitudinally forwardly of said frame and locking said beam in said notch during the initial upward movement of said beam and swinging the forward end of said scoop upwardly in a loaded position.

19. In a power shovel, the combination with a frame, a beam horizontally pivoted on said frame having a scoop pivoted to the free end thereof, means on said frame for elevating said beam and 20 scoop for discharging material rearwardly of said frame comprising a gear segment on said frame, a gear on said beam meshing with said gear segment, and power means for driving said gear, and means for controlling movement of

said scoop and moving said scoop longitudinally forwardly along the ground during the initial gathering operation comprising a slotted controlling link pivoted to said scoop at a point spaced downwardly from the axis of pivotal connection of said beam thereto, when said scoop is in an initial gathering position, and having slidable engagement with said beam in said slot, said slot leading to a notch at the end of said controlling link opposite the point of connection of said link to said scoop, and a member on said frame adapted to engage the rearward face of said link for initially swinging said scoop longitudinally forwardly of said frame and locking said beam in said notch during the initial upward movement of said beam and swinging the forward end of said scoop upwardly in a loaded position.

CHARLES E. STOLTZ.
